UNITED STATES PATENT OFFICE.

GUSS A. SWANSON, OF CHICAGO, ILLINOIS.

SWING.

Application filed September 4, 1925. Serial No. 54,448.

My invention relates to swings and has to do more particularly with swings of the character ordinarily employed on porches or lawns and which may be suspended from the 5 ceiling of a porch or from a frame set in the yard.

An object of my invention is to provide an improved structure of the above character and which may be more easily operated by 10 foot pressure.

Another feature of my invention is a simplified and more positive construction, whereby the swing moves in the direction of the operating force or foot pressure.

15 For a better understanding of my invention reference is to be had to the accompanying drawings, in which—

Fig. 1 is a side elevation of a single-seat swing of my invention suspended from a ceiling;

Fig. 2 is a perspective view of a removable table;

Fig. 3 is a right end elevation of Fig. 1;

Fig. 4 is a detail view showing the connection between the upper and lower sections of the hangers;

Fig. 5 is a side elevation of the swing of Fig. 1 in the position assumed by the swing when the foot pressure is first applied to start 30 the swing;

Fig. 6 is a view showing the double-seat swing; and

Fig. 7 is a perspective view of the framework and suspending structure alongside the seat of Fig. 6.

Referring now more in detail to the form of my invention as shown in Figs. 1 to 5, I will first refer in general to its operation. That is with the swing in normal position as shown in Fig. 1, the occupant places his feet against the foot boards and presses forwardly, applying pressure with each forward movement of the swing, the swing traveling in the direction of the applied force.

Now as to the construction, I provide a seat comprising end rails 10 having seat boards attached thereto and a back 11, preferably rigidly connected to the seat and having arm rests 12 suitably attached.

To the seat frame I attach the propelling and suspending means, consisting of a similar structure at each end of the seat and including intermediately pivoted suspending members. These suspending members are preferably rigid strips each including an up-

per strip 13 pivotally suspended at its upper end and a lower strip 14 pivotally attached to the seat frame at an intermediate point as 15, the lower end of the lower section being 60 pivotally attached to the foot-board frame at 16 and to the upper section 13 at 17.

The rear one of the suspending members is similar to the front one just described.

In Fig. 4 I show a detail view of the suspending or hanging members and their pivotal connections, the lower section 14 carrying an inner piece 18 with the seat end rail 10 pivotally supported between the two. The section 14 also carries at its upper end an 70 outer strip 19 so that the upper suspending member may be pivotally supported between the two.

I preferably arrange the suspending members so that they are adjustable and whereby 75 a single-seat swing may be adjusted according to the height from which it is suspended, and to this end the upper sections 13 are made of two halves including the part 13 and part 13', fastened together by the 80 bolts 20.

A suitable foot-board or actuating member is provided, consisting of the end sections 21 which are pivotally attached by the bolts 16, as already described, and having 85 the foot-boards 22 fastened thereto and arranged so that the foot may be applied without slipping.

In the operation of the swing of Figs. 1 to 5, and assuming it is suspended and hanging in its normal position as indicated in Fig. 1, the occupant is seated in the rigid seat and places the feet upon the foot-rest 22. The feet are now pushed forward and this throws the parts into the position indicated 95 in Fig. 5, that is with their central pivot moved back of the suspending points 23 at the top. This movement throws the seat forward of its normal position and beyond the center of gravity, so that as soon as the 100 pressure on the foot-board 22 is released the suspension members assume their straight position and the seat starts to move back. As it reaches its rear position the operator again applies forward pressure on the foot-boards 22, thereby again forcing the seat 105 upwardly, this movement being repeated so that in a few pushes the swing is moving back and forth to a suitable degree. When once started it requires but the slightest push 110 to keep it going, each application of power or push being made as the swing is moving

forward, so that it might be said that the direction of application of power and the movement of the swing coincide.

To stop the swing it is only necessary to apply the foot pressure in a reverse order, that is as the swing is traveling backward, which brings it to an immediate stop.

In Figs. 6 and 7 I have shown a double-seat swing which operates the same as the single-seat swing, that is by power applied in the direction of movement. That is as the swing is moving toward the left, the occupant of the seat at the right pushes forwardly on the foot-board and the opposite person does nothing. When the swing is moving toward the right, the occupant of the left seat pushes forward.

In the double-seat swing of Figs. 6 and 7 the side rail 21' for the foot-rest 22' is attached across the two suspending members, which instead of being attached to a single seat are each attached to a separate seat. The two seats are then rigidly connected together by a link 23 and braces 24, 25 and 26.

What I claim as new and desire to secure by United States Letters Patent is:

1. In a suspended swing of the character described a substantially horizontal rectangular seat frame, an upright back frame secured to the seat, an intermediately pivoted but otherwise rigid suspension member extending from the point of suspension to a point below the seat and pivotally attached to the side of the seat, said suspension member being pivoted between the point of suspension at its upper end and pivotal point of attachment to the seat, and a horizontally maintained foot-rest pivotally connected to the lower end of the suspension member, whereby forward pressure on the foot rest will move the seat in a like direction.

2. A suspended swing of the character de-

scribed comprising a substantially horizontal rectangular seat frame, a foot-rest positioned beneath the seat frame, and intermediately pivoted suspension members pivotally connected to each end of the seat frame and to the foot-rest, said suspension members being rigid downwardly from the intermediate pivot, the intermediate pivotal point of said suspension members being above the pivotal connection between the suspension members and seat frame, whereby intermittent application of pressure forwardly upon the foot rest will break the suspending members at said intermediate pivotal point and effect a swinging action of the seat having a movement coincident with the direction of pressure.

3. A suspended swing of the character described including a substantially horizontal seat frame, a back frame rigidly connected to the seat frame, a foot-rest, and suspension members pivotally connected to the seat frame and to the foot-rest and intermediately pivotally connected above the seat frame connection whereby the intermittent application of pressure forwardly upon the foot-rest will effect a swinging action having a movement coincident with the direction of pressure.

4. In a suspended swing, a seat, a foot-rest below and in front of the seat, having an extension under the seat, a pair of connecting members at each side of the seat pivoted to the seat and to the foot rest extension under the seat, and a pair of suspension members pivoted at one end to a suitable overhead support and at the other end to the upper portion of said connecting members above said seat.

In witness whereof, I hereunto subscribe my name this 13th day of April, 1925.

GUSS A. SWANSON.
